UNITED STATES PATENT OFFICE.

DON CARLOS TRAVIS, OF KENOSHA, WISCONSIN, ASSIGNOR TO THE SIMMONS MANUFACTURING COMPANY, OF KENOSHA, WISCONSIN, A CORPORATION OF WISCONSIN.

SPRING-MATTRESS FRAME.

1,071,827.

Specification of Letters Patent.

Patented Sept. 2, 1913.

Application filed February 15, 1912. Serial No. 677,803.

To all whom it may concern:

Be it known that I, DON CARLOS TRAVIS, a citizen of the United States, residing in the city of Kenosha, county of Kenosha, and 5 State of Wisconsin, have invented certain new and useful Improvements in Spring-Mattress Frames, of which the following is a specification.

This invention relates to improvements in 10 spring mattress frames and has for its salient object to provide simple and improved means for rigidly securing the side rails of the frame to the end rails without the use of bolts, screws, or other fastening devices. In 15 constructions of this character the end rails may take the form of angle irons while the side rails are generally tubular in form and lie in a plane below the wire fabric or mattress.

20 I am aware that heretofore attempts have been made to secure the side rails to the ends of the mattress by telescopic connection or by castings secured to the end rails and forming sockets for the side members. 25 None of these constructions however embody the simplicity and advantages of the present invention.

The invention consists in the matters 30 hereinafter described and more particularly 35 pointed out in the appended claims.

In the drawings Figure 1 is a top plan view of a bed frame embodying my invention, a portion of the metallic mattress being broken away. Fig. 2 is a side elevation of 40 the same. Fig. 3 is a fragmentary perspective view showing more clearly the manner of securing the sides to the end rails.

Referring to the drawings 1 and 2 designate 45 the end rails which in the present instance take the form of inverted angle irons and 3 and 4 the tubular side rails. The latter as shown in the drawings lie in a plane below the metallic fabric and are bent upwardly at either end as shown at 5, 5. Each 50 end of the side rails is flattened as shown at 6 and the flattened ends extend through apertures or slots 7 formed in the outer flanges 8 of the end rails. When the extremities of the side rails are inserted in the slots 7, the former are bent downwardly 55 as shown at 9, so as to lie flat upon the upper faces of the flanges 8. The side rails are secured to the end members without the use of any extraneous fastening devices of

any kind. At the same time the frame members are rigidly and permanently united and in such a way as to prevent any possibility of lateral or endwise movement of the side rails. There is little or no possibility of the parts working loose and the construction at 60 the same time is obviously very simple and economical. The fabric 10 is secured to the end rails by means of flat plates 11 which may be riveted or otherwise fastened to the inner flange 12 of the angle irons 1 as shown 65 at 13. The manner of securing the fabric to the frame however, forms no part of the present invention.

The essence of the present invention consists in its simplicity and reliability in construction and no extended description of the manner in which it is assembled is necessary. The frame as a whole is supported on the bedstead (not shown) in the usual manner, i. e., the outer flanges 8 rest upon the end 70 members of the metal bedstead. The invention is not limited to the detail construction shown, except as set forth in the appended 75 claims.

I claim as my invention:

1. The combination with a pair of angle irons lying in inverted position and forming the end rails, of a metallic mattress secured to the inner flanges of said end rails, a pair of tubular metal side rails lying in a plane 85 below the mattress and bent upwardly at either end, the extremities of said side rails being flattened and projecting through short slots in the outer flanges of the end rails and bent downwardly against the faces of 90 the angle irons to lock said rail members together against lateral or endwise movement relative to each other.

2. In a mattress frame, the combination 95 with a pair of angle irons forming end rails, of a pair of tubular side rails lying in a plane below the end rails and bent upwardly at either end, the extremities of said side rails being flattened and extending through short slots formed in said angle irons and 100 bent downwardly against the faces of said angle irons to lock said rail members together against lateral or endwise movement relative to each other.

3. In a mattress frame, the combination 105 with a pair of end rails, of a pair of side rails, the extremities of said side rails projecting through small slots formed in said

end rails and then bent inwardly to lock said rail members together against lateral or end-wise movement relative to each other.

4. In a mattress frame, the combination with a pair of end rails, of a pair of side rails, the ends of one pair projecting through small slots in the other pair and then

bent inwardly at their extremities to lock the rails together to form the frame.

DON CARLOS TRAVIS.
